US00D610600S

(12) **United States Design Patent**
Sheppard et al.

(10) **Patent No.:** US D610,600 S
(45) **Date of Patent:** ** Feb. 23, 2010

(54) **DIGITAL VIDEO CAMERA WITH BUILT-IN CONNECTOR**

(75) Inventors: **Nasahn Adam Sheppard**, Mill Valley, CA (US); **Maarten Dinger**, San Francisco, CA (US); **Allan Freas Velzy**, San Francisco, CA (US); **Peter Michaelian**, Tappan, NY (US); **Jaewon Samuel Kang**, Santa Clara, CA (US); **Lionel Jingles**, San Francisco, CA (US); **John Louis Warpakowski Furlan**, Belmont, CA (US); **Greg Allen Cummings**, San Francisco, CA (US)

(73) Assignee: **Cisco Technology, Inc.**, San Jose, CA (US)

(**) Term: **14 Years**

(21) Appl. No.: **29/328,155**

(22) Filed: **Nov. 19, 2008**

CLAIM

The ornamental design for a digital video camera with a built-in connector, as shown and described.

DESCRIPTION

FIG. 1 is a front perspective view of a digital video camera with a built-in connector showing our new design.

FIG. 2 is a rear perspective view thereof.

FIG. 3 is a front perspective view thereof, with the connector being in an extended position.

FIG. 4 is a rear perspective view thereof, with the connector being in an extended position.

FIG. 5 is a right side elevational view thereof, with the connector being in an extended position.

FIG. 6 is a left side elevational view thereof, with the connector being in an extended position.

FIG. 7 is a top view thereof.

FIG. 8 is a top view thereof, with the connector being in an extended position.

FIG. 9 is a front elevational view thereof, with the connector being in an extended position; and,

FIG. 10 is a rear elevational view thereof, with the connector being in an extended position.

The broken line portions in all views are shown to illustrate environment only and form no part of the claimed design.
